UNITED STATES PATENT OFFICE.

LOUIS J. VAN GUELLEN, OF CINCINNATI, OHIO.

MACHINE FOR FINISHING THE EDGES OF FLEXIBLE MATERIALS.

Application filed November 5, 1919. Serial No. 335,944.

To all whom it may concern:

Be it known that I, LOUIS J. VAN GUELLEN, a citizen of the United States, residing at the city of Cincinnati, in the county 5 of Hamilton and State of Ohio, have invented certain new and useful Improvements in Machines for Finishing the Edges of Flexible Materials, of which the following is a specification.

10 I have produced this machine for finishing the edges of flexible materials in order to carry into execution the process for finishing the edges of flexible materials, and I will here describe this process and its 15 steps so that this present invention will be more fully understood. I hereby describe said process as follows, and it is fully set forth in my application for a patent therefor now filed in the United States Patent 20 Office as Serial No. 326,658, from which I quote the following:

“My invention relates to simple, yet efficient steps, to finish the edges of flexible materials of any kind. In the manufacture of certain parts of shoes, say for example, vamps, uppers and tips, it has been usual to turn the edges or fold them to make a finished job. I propose to eliminate the folding operation and finish 25 the edge, so that it will appear rounded or symmetrical in contour and to color or treat the edge with some fluid, and then burnish the same. By this process I present a highly desirable finished edge of any kind 30 or shape desired and by treating the same with a coloring fluid, I can retain the color of the fabric at the cut or raw edge; and if I desire to use a waterproofing fluid or compound, I form a waterproof edge; and 35 if I wish to strengthen the edge or make it harder or softer I may use some other suitable fluid for such purpose. After this edge has thus been treated, to wit: formed and the proper fluid applied thereto, then I 40 burnish said edge to form a finished edge, which will appear polished and smooth and give the same appearance as the finished side of the stock out of which the shoe is 45 made.

50 My process consists of the following steps or stages, and as I am describing the operation of the process, I will refer to treating and finishing a patent leather vamp.

“First—I take the vamp and along its

raw edge, which is to be finished, I apply 55 any mechanism which will trim, cut, form, press or otherwise cause said edge to be molded or formed, for example, into a ‘rounded edge form’; secondly—I then apply to this rounded edge a highly lustrous 60 waterproof fluid, and thirdly—I subject the edge thus treated, to a burnishing, or polishing element or operation, which brings out the bright lustrous finish or polish similar to the patent leather color, and finish on the 65 shoe and makes it smooth and uniform. In the present example the edge thus treated is as pliable as the patent leather itself and will not crack, break or scale off, and appears the same as the finish of the leather 70 itself.

“In carrying out my process, I may use any mechanism for forming the edge of any desired shape, and may use any kind of the color matter, or fluid, or oily substance, or 75 compound or composition of matter; and I may use any form of polishing or burnishing element or tool.

“If it is desired to use the raw edge, and color or treat it as desired with the fluid, 80 and then burnish it, the forming operation first described is not used.

“While I have herein specifically referred to leather edges, I may use my process in connection with any other kind of flexible 85 material and I may use it in connection with any kind of articles of manufacture or parts of same.”

I preferably employ the machine herein described for carrying this process into 90 effect as before herein first set forth.

In this machine I have combined elements for trimming and molding the edge of the leather, treating the same, and burnishing the same, in a unique and novel manner. 95

In the accompanying drawings, forming part of this specification:

Fig. 1, is a side view of the machine, and its frame, the frame being shown in section,

Fig. 2, is a plan view of the machine, the 100 work support being removed,

Fig. 3, is section on line 3—3 of Fig. 2, parts, however, being shown in elevation and broken away,

Fig. 4, is a section on line 4—4 of Fig. 1, 105

Fig. 5, is a section on line 5—5 of Fig. 1,

Fig. 6, is an end view of the presser foot mechanism,

Fig. 7, is a sectional view of the lower guide mechanism and the feed wheel,

Fig. 8, is an enlarged section of the cutting and polishing tools,

5 Fig. 9, is an enlarged sectional view of the cutting tool,

Fig. 10, is a section on line 10—10, of Fig. 9,

10 Fig. 11, is a section of the inking mechanism,

Fig. 12, is a plan view of the lower guide mechanism and its levers,

15 Fig. 13, is an elevation of the lower guide mechanism, without its levers,

Fig. 14, is a section on line 14—14, of Fig. 12,

Fig. 15, is a view in elevation of the outer sleeve of the lower guide mechanism, and

20 Fig. 16, is an elevation of the inner sleeve of the lower guide mechanism.

I will first describe the means for trimming, cutting or shaping the edges of the leather. For this purpose, I provide a spindle 1, carrying a knife or cutter head 25 formed of a lower part 2 and an upper part 3, the upper part capable of being placed into the lower part, and these parts are held together by a slide stud 4 passing into a slot 5 in the lower part 2; this slot allows 30 the knife or cutter head parts to move toward or away from each other to accommodate varying thicknesses of leather between the cutting edges of the knives or cutters. The lower and upper parts of this knife or 35 cutter mechanism may be termed a cutter head, and the lower part may be called the outer element and the upper part the inner element of the cutter head; the inner part sliding in the outer part. The cutter head 40 is held on the spindle 1 by the pin 6. To keep the upper (or inner) knife part 3 in normal position, a spring 7 is provided 45 around the spindle 1 which abuts against said upper (or inner) part 3 at its top and abuts against a buffer or polisher placed on the spindle 1 above the cutter head; this 50 spring 7 is stressed when the leather is placed between the cutting edges 8 and 9 of the parts 2 and 3, and when cut or formed, 55 the spring relaxes and the parts are again normal. It may be stated that some real thin pieces of leather might not stress the spring 7. The cutting edges 8 and 9 of the knife parts 2 and 3, trim, cut or shape the 60 edge of the leather to suit the particular job being worked upon, and they may be changed and other shaped cutting knives be used to cut and shape other styles.

65 The next step in the method, is to color, wet, oil or place liquid of some kind on this cut or shaped edge, or some plastic composition or matter may be used. To carry out this step I employ a receptacle 10 placed on a swinging arm 11, pivoted to the frame 70 of the machine at 12. To the receptacle 10,

I connect a hollow tube 13 which carries at its end a well 14, into which I place a felt plug 15; the fluid or material to be used is marked 16 and passes from the receptacle 10 through hollow arm 13 into the well 14, 70 to saturate the plug 15, a valve 17 controlling the flow of the material 16.

75 After the edge of the leather has been trimmed or shaped, and treated with material as just set forth, I burnish, polish or buff said formed edge, and use, preferably, the following means for doing such work; on the spindle 1, I place a burnishing, polishing or buffing tool, roll, or wheel, in the present instance, formed of a multiplicity 80 of discs or rings 18, made of felt or any other suitable material or fabric, which are placed between a collar 19 and a flanged housing or bearing 20, the flanged housing screwing into the collar 19, the housing being held on the spindle by pin 21.

85 Now that I have described the various parts or steps of the machine used in carrying out my method of finishing the edges of materials, I will describe how they are 90 operated and used. The frame of the machine is marked 30; this frame supporting a cross piece 31. At the top of the frame I place a work support or plate 32 on which I support an upwardly and forwardly extending arm 33. In bearings 34, 35 and 36, I support the drive shaft 37, carrying drive pulley 38. On shaft 37, I place a spiral 39 which meshes with a spiral 40 on short shaft 41, which carries a worm 42 100 meshing with worm wheel 43, on a short shaft 44, on which is placed the feed wheel 45, thus this said feed wheel is turned when the shaft 37 is operating. The feed wheel 45 extends slightly above the face of work 105 support or plate 32, (see particularly Fig. 4).

110 The spindle 1 is supported in bearings 46 and 47 (see particularly Fig. 5). On the main drive shaft 37 I place spiral 48 which meshes with spiral 49 on spindle 1. At the lower end of the spindle 1, I place a sliding bearing 50, moved up and down by a rack 51 rigidly attached to bearing 50 and meshing with a gear 52 attached to a shaft 53, 115 held in bearings 54 on support 31, and said shaft is rocked or oscillated by a lever 54¹, to move the spindle up to bring the cutting means into alignment with the work support 32 and down to bring the buffing or 120 burnishing means in alignment with the said work support 32, (see particularly Fig. 2). At the end of this lever 54¹, I place a centering pin and handle 55 which pin enters a hole (not shown) in the frame to properly 125 align the cutting and burnishing tools with the work support or plate 32, which is known as the feed plate.

130 I will now describe the presser foot mechanism which operates above the work sup-

port or plate 32. At the forward part of the arm 33, I provide a bracket 56, provided with two bracket arms 57 and 58. At its forward end, this arm has a downwardly extending arm 59 to which I attach an auxiliary arm 60, provided with a cam race 61, (see particularly Fig. 1). In the arms 57 and 58 I support a shaft 62, carrying at its lower extremity block or head 63. This block or head carries a fork 64 which will be hereinafter described. This block also carries a stud 65 which passes into and through cam race 61 and also through cam roller 66, which operates in the cam race. At the top the shaft 62 is provided with a removable spool 67 into the web of which fits the fork end of the lever 68, fulcrumed at 69 on arm 33; this lever extends backward and downward, terminating in a finger hold 70. On the shaft 62 I place a collar 71 and between this collar and the lower face of the bracket 58 and around the said shaft 62, I place a spring 72. In the bracket arms 57 and 58, I also carry and support a shaft 73, which operates up and down and revolves loosely in said bracket arms. At the lower end of shaft 73 I connect a presser foot, presser wheel or disc 74. The fork 64 passes in a groove in each side of the hub 75 of the presser wheel. To the forward end of the fork 64 I attach a guide arm 76, having a foot 77. The bracket 56 is pivoted at 78 to the forward extension 79 of the arm 33 (see Fig. 6). The shaft 62 and its parts, and the shaft 73 carrying the presser wheel, are moved up and down by manipulating the lever 68, and by reason of cam roller 66 passing over the cam race 61, the parts just set forth are moved up and down, and they also move outwardly and inwardly together with the bracket 56 on the pivotal point 78; more particularly, first moving upwardly, then outwardly and then again upwardly, and in the downward movement, first going downwardly then inwardly and then downwardly; the peculiar shape of the cam and cam race permitting this movement. These parts which have just been described as swinging or moving in and out, and up and down, are set at an incline or angle as shown in Figs. 1 and 6, and they form a pressure device for pressing down the material onto the feed wheel 45.

I will now describe the lower feeding and guiding means, which are below the work support or plate 32. I provide a bearing or supporting flanged sleeve, composed of flange 80 and sleeve 90 suitably united together; the flange 80 is screwed to the work support or plate 32 and lies flush therewith, except at the point 82 which is recessed, and at this point feed wheel or roller 45 extends above the level face of said flange 80, at which point, at each side of the recess 82, it is flared upward at the top at 83 and beveled at the lower part 84. At the point 85 at each side, at the rear of recess 82 and at the border of the central hole 86 in the flange, I place two inwardly extending fingers. These fingers are raised at their upper surfaces to the same plane as the raised parts 83. At one side of the hole 86 the flange is cut away at 87, to form space for the lower guide pin 88 to travel, which will be more particularly hereinafter set forth. The flange 80, has near its inner edge, adjacent to the central hole 86, but somewhat larger in diameter, a downwardly extending connecting extension part 81, cut away at 89 as shown, to make room for the feed wheel or roller 45. The sleeve part 90 of the flanged sleeve extends downwardly therefrom and is rigidly connected to said flange through the medium of extension 81. In this sleeve 90, I place the race way or cam race 91. In this sleeve 90, I place another sleeve 92. At the top edge of the sleeve 92, I place an upwardly extending guide pin 88 which operates in the passage way 87 in flange 80. At the bottom edge of the sleeve 92, I connect an outwardly extending lever 93 provided with a slot 94, and this lever oscillates the sleeve 92. To the sleeve 92 at one side, I place a stud 95, and cam roller 96 is loosely connected thereon. This cam roller operates in the cam race 91 in sleeve 90. This cam roller 96, operating in the cam race (on account of the peculiar shape of said cam race), raises the sleeve 92 up and down in the sleeve 90, consequently the pin 88 is raised and lowered. The edge of the leather or other material to be burnished, is guided by the pin 88, by reason of the said leather being pushed against and held against the same, thus keeping the leather in alignment and preventing its crowding into the cutting and burnishing tools, as the cutting and burnishing is proceeding.

The short lever 93 is operated by a short lever 97 fulcrumed at point 98, a stud 99 on the lever 97 operating in slot 94, in the lever 93. This lever is loosely connected at point 100 to a handle lever 101, fulcrumed at 102. By pushing the handle lever 101 to the right, causes a reverse action on lever 97, this in turn oscillates lever 93, through medium of the stud 99 moving in slot 94. These levers are thrown back into normal position by suitable spring action (not shown).

In operating the machine, the spindle 1, which carries a cutter head formed of knife carrying parts 2 and 3 and the burnishing tool or element 18 is put into operation, so that it will revolve at high speed by operating drive shaft 37 which meshes with mechanism heretofore described in detail; the feed roller or wheel 45 being also revolved by said shaft 37 and its connections as heretofore set forth in detail. The spin-

dle 1 is raised and lowered by means of gear and rack means as heretofore set forth; it is raised and lowered to place the cutting means or the polishing element in alignment and register the same with the work support or plate 32. This raising and lowering is done by means of the lever and center pin raising or lowering the spindle by moving the gear 52 which meshes in rack 51, thus 10 pulling the spindle 1 up and down as needed for either the cutting means or for the burnishing means. The cutting means are first adjusted and brought into alignment with work support or plate 32, the leather article, 15 or any other material, is then placed between the presser wheel 74 and the feed wheel 45, and automatically fed through, the cutting knives 8 and 9 trimming and forming the edge of the desired contour or 20 shape. In placing the material in position to be fed through and worked upon by the knives, it is guided against the pin 88, which keeps the material from crowding into the knives. This pin is operated through a system of levers 93, 97 and 101, which are 25 manually operated as heretofore described. This pin can be brought up into operative position, or it can be moved below the plate when its use is not required.

30 The presser wheel 74 presses against the material to keep it on the feed wheel 45, that proper feeding may result and the guide 77 keeps the material from buckling at the edges, or turning up at said edges, 35 as it is brought in contact with the cutting or burnishing tools. When short or small inside curves are present in the work being operated upon, the guide pin 88 need not be used, as such curves will hug and remain 40 in proper position in relation to the cutting tools and burnishing tools. The presser means are pivoted to swing at point 78, and through manipulation of lever 68, can be moved up and down and in and out, as 45 heretofore set forth. The same feeding and pressing mechanism are used in connection with the cutting and polishing or burnishing elements. These means for feeding the material to the cutting knives and to the 50 burnishing element are fully set forth in an application which I made for improvements in burnishing machines, filed in the United States Patent Office, Serial No. 335,516, and reference is hereby made thereto for a more 55 detailed description. After the edges have been trimmed or cut and properly shaped by the knives, I take a batch of the articles so finished, to the device 10, where the edges are passed over a plug 15 carrying the material to be placed onto said edges. Then the 60 burnishing tool 18 is brought into alignment with work support or plate 32, and the batch of articles are polished or burnished and finished to the desired degree.

65 By trimming the edges with knives or

cutting devices or abrasion means, and treating the edge thus shaped and formed as specified, and then giving said edge a burnished or polished surface and appearance, I provide a new article of manufacture; as 70 for example, if shoe vamps are thus treated, said vamp will have an edge thereon, not now present in vamps of this character, and the same may be said of other articles of manufacture in which such an edge is needed or desirable; especially is this true when 75 flexible leather, (for example, patent leather), or such like flexible material is used.

I wish to be understood as not confining myself to the specified mechanism herein set forth in describing my machine, inasmuch as the same is capable of considerable modification and change, without departing from the principle of my invention, and I further wish to be understood that claiming that such modifications and changes will still fall within the scope of my invention.

What I claim as new and my invention and desire to secure by Letters Patent, is:

1. In a machine of the character described, a revolving spindle, a work supporting plate, means for feeding and holding the material to said spindle, said spindle capable of being raised and lowered, and a guide means for guiding the edge of the material being worked upon.

2. In a machine of the character described, a revolving spindle, a work supporting plate, said spindle capable of being moved up and down, and carrying means for cutting and means for polishing the edge of a flexible material.

3. In a machine of the character described, a work supporting plate, and a revolving spindle, said spindle having a cutter head thereon and a burnishing tool, and capable of being moved up and down to align either said cutter head or said burnishing tool with said work supporting plate.

4. In a machine of the character described, a work supporting plate and a revolving spindle, said spindle having a cutter head thereon and a burnishing tool, and capable of being moved up and down to align either said cutter head or said burnishing tool with the work supporting plate, and means for feeding material to said cutter head and to said burnishing tool.

5. In a machine of the character described, a work supporting plate and a revolving spindle, said spindle having a cutter head thereon and a burnishing tool, and capable of being moved up and down to align either said cutter head or said burnishing tool with the work supporting plate, and means for feeding material to said cutter head and to said burnishing tool, and movable means for exerting pressure on the material while the same is fed to the spindle.

6. In a machine of the character described, a revolving spindle and a work supporting plate, said spindle carrying means for trimming and means for polishing the edge of flexible material, and means for guiding the material and pressing upon the same as it is being worked upon, said means

being capable of continual operation, and manually thrown out of operative position, at will.

In testimony whereof, I affix my signature at Cincinnati, Ohio, this 18th day of September, 1919.

LOUIS J. VAN GELPEN.
